CLAIM

The ornamental design for a CD-ROM video game machine, as shown and described.

DESCRIPTION

FIG. 1 is a top view of a CD-ROM video game machine, showing our new design;

FIG. 2 is a front elevation thereof;

FIG. 3 is a right elevation thereof;

FIG. 4 is a left elevation thereof; and,

FIG. 5 is a rear elevation thereof.

The broken line showing of a housing is for illustrative purpose only and forms no part of the design.

FIG. 1

FIG. 2

FIG. 3**FIG. 4**

FIG. 5
